UNITED STATES PATENT OFFICE

ALBERT R. ACHESON, OF SYRACUSE, NEW YORK, ASSIGNOR TO E. C. STEARNS & CO.,
OF SYRACUSE, NEW YORK, A CORPORATION OF NEW YORK

INCINERATOR

Application filed July 2, 1926. Serial No. 120,108.

This invention relates to incinerators or furnaces installed in dwellings, apartment houses, etc., for burning rubbish, refuse, garbage and the like and has for its object means by which a draft is provided for drying and carrying off the odors of the material within the furnace incinerator when the contents are not burning, as well as the furnace air to support combustion.

It further has for its object an arrangement of the direct air passages whereby the odor from the material within the furnace is prevented from escaping into the cellar or basement of the building in which the incinerator is installed.

The invention consists in the novel features and in the combinations and constructions hereinafter set forth and claimed.

In describing this invention, reference is had to the accompanying drawings in which like characters designate corresponding parts in all the views.

Figure 1 is a front elevation of an incinerator embodying my invention.

Figure 2 is a sectional view on line 2—2, Figure 1.

Figures 3 and 4 are sectional views taken respectively on lines 3—3, and 4—4, Figure 2.

This incinerator comprises generally, a body provided with a combustion chamber, a flue leading therefrom serving both as a chimney flue and as a conduit through which rubbish, garbage and other refuse is conveyed to the incinerator, a direct air passage leading from the outside of the incinerator to the combustion chamber thereof, the inlet for such passage being out of line with the outlet thereof into the combustion chamber and preferably below the outlet.

The air intake from the outside of the combustion chamber is open at all times permitting a continuous air circulation for drying, burning, or carrying off of odors.

1 designates the body which is usually formed of brick.

2 is the combustion chamber.

3 is the flue leading therefrom.

4 is the grate and 5 is the ash pit below

50 the grate.

6 is a door leading into the combustion chamber and 7 is the ash pit door.

The direct passages are here shown as built into one of the walls of the body 1 and arranged to open into the combustion chamber beneath the overhanging wall 8 of the top of the body. 55

As here shown, one of the walls is formed double providing an upright passage 9 having a plurality of vertical slots or outlets 10 opening into the combustion chamber 2 and also having inlets 11 opening into the outer air near the base of the body 1 or beneath the combustion chamber or the level of the grate 4. 60

A door leads into the flue or chimney at each floor of the building, through which the rubbish, garbage, etc., is deposited in the flue. 65

In operation, the rubbish is usually thrown into the chimney 3 from the various floors or of course, it may be inserted through the door 6. At intervals, it is ignited. Before the rubbish is ignited, ample air draft is provided through the chimney and the direct air passages and hence, the material is dried and odors from the material are carried off and there is no liability of the odors escaping down through the direct passages and the inlets 11 below the level of the grate 4, owing to the fact that ample draft is provided for. 70

When the material in the combustion chamber is ignited and burning, the draft through the direct passages is ample to support combustion, it being understood that often-times on account of the quantity of the material on the grate, air can not pass through the grate. Also, while the material is lying on the grate, but not burning, 75 the positive draft through the direct air passages drives out the moisture from such material and prepares it for burning. 80

What I claim is:

1. In a garbage incinerator, the combination of a body formed with a combustion chamber and an ash pit, a flue leading from the chamber, the body being formed with a permanently open upright passage in one of its side walls and with outlet 95 100

passages opening from the first passage laterally into the combustion chamber and with other passages opening through the outer wall of the body serving as an inlet to the air, the latter passages being located below the outlets into the combustion chamber, all of said passages having no direct communication with the ash pit.

2. A garbage incinerator comprising a body provided with a grate, a combustion chamber above the grate, an ash pit below the grate and a combined smoke flue and inlet for the material to be consumed leading from the top of the body, the top also providing an overhanging wall, permanently open air passages leading from the atmosphere outside of the body and having outlets opening directly into the combustion chamber above the grate under the overhanging wall to supply air to support combustion, said passages having no direct communication with the ash pit.

3. A garbage incinerator comprising a body provided with a grate, a combustion chamber above the grate, an ash pit below the grate and a combined smoke flue and inlet for the material to be consumed leading from the top of the chamber, the body being formed with an upright passage in one of its side walls and with outlet passages opening from the first passage laterally into the combustion chamber, said lateral passages extending vertically slightly above the grate to the top of the chamber, the body also having other passages opening through the outer wall of the body serving as an inlet to the air, the latter passages being located below the outlets into the combustion chamber, all of said passages having no communication with the ash pit.

In testimony whereof, I have hereunto signed my name at Syracuse, in the county of Onondaga and State of New York, this 30th day of June, 1926.

ALBERT R. ACHESON.
